(57) **CLAIM**

The ornamental design for a vehicle taillamp, as shown and described.

DESCRIPTION

FIG. 1 is a front view of a vehicle taillamp according to a first embodiment of the invention.

FIG. 2 is a left side view thereof.

FIG. 3 is a bottom view thereof.

FIG. 4 is a top view thereof.

FIG. 5 is a front view of a vehicle taillamp according to a second embodiment of the invention.

FIG. 6 is a left side view thereof.

FIG. 7 is a bottom view thereof; and,

FIG. 8 is a top view thereof.

The mirror image of each embodiment is within the scope of the claimed design even if not illustrated.

Features shown in broken lines do not form part of the claimed design.

1 Claim, 8 Drawing Sheets
